HOMER L. ROGERS, OF DAYTON, OHIO, ASSIGNOR TO THE PHILIP CAREY MANUFACTURING COMPANY, A CORPORATION OF OHIO

RAIL FILLER

Application filed June 4, 1930. Serial No. 459,150.

My invention relates to rail fillers and is more particularly addressed to providing a rail filler consisting of a plurality of members, one or more or all of which have been 5 preformed in a factory so that one member may be used as a locking or wedging means to hold the filler in place in the rail.

In the drawing I have shown the cross section of a rail having my improved rail 10 filler on the left of the web of the rail. In the drawing 1 is the rail; 2 and 3 constitute a rail filler, 3 being a sheet of prepared roofing formed of a sheet of felt saturated with a bitumen. Such a felt is flexible, elastic and 15 somewhat plastic, by reason of its bitumen saturation.

As shown, the member 3 of the rail filler is placed in the rail against the web and the top of the base, after which the member 2, 20 which is a preformed wedged shape member is introduced in the side of the rail and by means of a mallet, hammer or other suitable means is forced into the rail wedging the member 3 firmly against the upper side of 25 the base of the rail and thereby locking the rail filler members 2 and 3 firmly in position between the ball and the base of the rail. The lower edge portion of the sheet 3, as shown, extends outwardly beyond the lower 30 outer longitudinal edge of the block-like member 2, providing an apron insulating the rail from the adjacent paving.

The member 2 I preferably form to the desired shape in a factory from a material composed of a bitumen, preferably asphalt, a 35 fibrous material either vegetable, animal or mineral and if a harder product is desired I also use pulverulent or granular minerals. If desired, and I have found it satisfactory 40 in some instances, the wedged shape filler member 2 may be of a less plastic like nature or a more solid and hard nature than the member 3. This insures greater ease in installing the fillers and a more positive sealing effect between the filler and the rail.

I claim:

1. In a rail filler a plurality of plastic members adapted to form a filler between the base and the ball of a rail.
- 50 2. In a rail filler a plurality of members

containing bituminous material and adapted to form a filler between the base and the ball of a rail, one of said members being a preformed wedge to hold said filler in the rail.

3. In a rail filler a preformed member containing a bituminous material and a plastic member adapted to hold said first mentioned member in the rail.

4. In a rail filler a member of a plastic 60 like material, a separate preformed member containing bituminous material and adapted to form a wedge to hold both of said members in a rail.

5. In a rail filler a member of a plastic like 65 material, a separate preformed member containing bituminous material and of a more rigid and less plastic character adapted to form a wedge to hold both of said members in a rail.

6. In a rail filler a flexible member, a preformed relatively solid member containing bituminous material and adapted to form a wedge to hold both of said members in the rail.

7. In a rail filler consisting of a plurality of members containing bituminous material, one of said members adapted to contact with the upper surface of the base of the rail and another member engaging with said member 80 to hold said rail filler in position.

8. In a rail filler consisting of a plurality of preformed members of plastic like material containing bitumen, one of said members forming a wedge to hold the filler in the rail.

9. A rail filler of the class described, comprising a preformed block-like compressible member adapted to substantially fill the space between the head and base of a track rail, and an insulating covering for one side 90 of the block, one of the longitudinal edges of the covering extending beyond a longitudinal edge of the said block-like member and providing an insulating apron substantially as and for the purpose described.

10. A rail filler of the class described, comprising a preformed block-like compressible member adapted to substantially fill the space between the head and base of a track rail, and a waterproofed sheet of felt con- 100

tacting one side of the block, one of the longitudinal edges of the sheet extending beyond a longitudinal edge of the said block-like member and providing an insulating apron, substantially as and for the purpose described.

11. A rail filler of the class described, comprising a preformed block-like compressible member adapted to substantially fill the space between the head and base of a rail, and an insulating apron attached to and extending beyond one of the edges of the member substantially as and for the purpose described.

12. A rail filler of the class described, comprising a preformed block-like compressible member adapted to substantially fill the space between the head and base of a rail, and an insulating apron of waterproofed felt attached to and extending beyond one of the longitudinal edges of the member substantially as and for the purpose described.

In testimony whereof, I have signed my name to this specification.

HOMER L. ROGERS.
